UNITED STATES PATENT OFFICE.

PAUL LEONIDE BAUDRY, OF PARIS, FRANCE.

BOTTLING MINERAL WATERS.

1,252,535.

Specification of Letters Patent. Patented Jan. 8, 1918.

Application filed March 31, 1914. Serial No. 828,505.

To all whom it may concern:

Be it known that I, PAUL LEONIDE BAUDRY, citizen of the French Republic, residing at Paris, Department of the Seine, in 5 France, have invented certain new and useful Improvements in Bottling Mineral Waters; and I do hereby declare the following to be a full, clear, and exact description of the invention, such as will enable others 10 skilled in the art to which it appertains to make and use the same.

In the practice of bottling mineral waters, it has been customary to clean and sterilize the bottles or containers and then fill the latter with an innocuous gas, such as carbonic acid gas, to prevent contamination of the bottles, such as might be produced by contact with atmospheric air, prior to the filling operation. The presence of this excess of 20 carbonic acid gas has been found objectionable and deleterious, in certain cases in which mineral waters carry constituents, which would be obviously affected by such excess of carbonic acid gas.

25 The present invention has for its object to provide an improved process of bottling mineral waters and the like, so that the properties of the mineral water will be unchanged in spite of the presence of carbonic acid in the container.

To this end the invention comprises reducing the pressure of the gaseous medium in the bottle or container, prior to the admission of the water or the like to the container, 35 until the gaseous pressure in the container is equal to the pressure or tension of the gas, which is maintained in solution or suspension in the water or the liquid. That is to say, instead of reducing the pressure in the 40 containers to a point as nearly approximating a vacuum as possible, as has heretofore been the practice, the pressure of gas in the containers is reduced to a point where it approximates, but is never less than the tension 45 of the gas in the water or liquid to be bottled. For example, if the water contains gas under a tension of .02 atmospheres, which means that the gas would escape from the liquid if the pressure on the liquid were 50 reduced to a point below .02 atmospheres, the pressure of the carbonic acid gas or the gaseous medium with which the containers have been previously filled, is reduced to approximately .02 atmospheres, after which the 55 water or liquid is admitted to the containers,

and passes into the same without encountering any conditions which would tend to liberate or dissociate the gaseous constituents thereof.

There are certain medicinal waters which 60 contain useful solid matters, such as colloidal iron, which matters are maintained in their state of suspension or equilibrium because of the presence of particular quantities of free carbonic acid. It is, therefore, 65 advisable, for the purpose of preserving the composition of said waters without impairment, not to add carbonic acid to the same, as this makes the use of the process described impossible. Furthermore, it is necessary 70 to avoid the disappearance of the small quantity of free carbonic acid, as its elimination would produce precipitation of the solid matters.

In order to carry out this bottling of the 75 water with incomplete rarefaction of the carbonic acid or other gases with which the bottle is filled at atmospheric pressure, the said bottle, instead of being connected directly to the vacuum tank when in place on the machine, is connected to an auxiliary tank in which as perfect a vacuum as possible has been produced. The volume of this auxiliary tank is such that the carbonic acid supplied to the bottle at atmospheric pressure 80 assumes the desired pressure when the water enters the bottle by expanding in the bottle and the auxiliary tank. In the example previously mentioned, when it is desired to arrive at a pressure of 0.2 atmospheres during the bottling of the water, and assuming that the volume of the bottle is one liter, the capacity of the auxiliary reservoir 85 is made four liters. This the gas contained in the bottle when the water is introduced into the latter will pass entirely into the auxiliary tank at the end of the bottling operation and will thus occupy a space four times greater than that of the bottle. Its pressure will be reduced, therefore, to 90 about one-quarter of an atmosphere. That is to say, if the bottling is started at 0.2 atmospheres, it will be finished at 0.25 atmospheres. This final pressure, is, therefore, 95 slightly higher than that at the beginning. However, it is necessary, in order to avoid any disassociation of materials in the water, that the pressure never fall below 0.2 atmospheres and the rapidity with which the operation takes place is such that the maxi- 100 105 110

mum pressure is attained only at the end of the operation, and thus the solution of even a small proportion of the gas is impossible.

In the accompanying drawings:—

Figures 1 and 2 show, by way of example, two constructions of apparatus for carrying out the process.

In the device shown in Fig. 1, the bottle 18, which has been previously filled with carbonic acid in the manner above described, is placed on the bottling machine provided at its upper portion with a casing 9 and with two cocks 8 and 16, the cock 8 being in the pipe 21 which leads from the casing to the vacuum tank 22, and the cock 16 being in a pipe 20 which is connected to the source of supply of mineral water.

The bottle 18 is placed on a device which locates it under a rubber washer of the casing 9, and thence under a casing 30 of the corking machine without permitting the mouth of the bottle to come in contact with the air. Specifically, the bottle 18, which is filled with carbonic acid, is placed on the disk 25 of the bottling and corking machine and by means of the cock 8 and the tank 22, a partial vacuum is instantaneously produced in the bottle and the cock is closed. The cock 16 is then opened and a suction is produced, owing to the difference of pressure, and the water from the source passes through the pipe 20 into the bottle and fills the latter.

This water is conveyed to the bottle in the following manner:—

A pure tin siphon 24 is provided, which conducts the water from the source 25' at a depth of, for instance, two meters, into a basin 26, because of the difference in pressure, the basin 26 being at a level from three to three and one-half meters lower than that of the source 25. This siphon passes through the bottling room at a height of about three meters from the floor, in actual practice. From the upper portion of the siphon, the pipe 20 branches, which pipe is also of pure tin and descends vertically above the bottle, opening into the casing 9. This pipe includes a portion 29, in the interior of which a check-valve 28 is located, which valve closes under an excess of pressure in the pipe 20. At the point of intersection of the U-shaped pipe with the siphon, a three-way cock 23 is arranged by means of which the flow in the siphon may be deviated at will toward the bottle until the latter is completely filled. The cock may then be turned so that the water will flow again through the siphon. This arrangement makes it, therefore, possible to always have available running water for bottling, which water is brought to the highest point in the siphon by natural pressure, and thence passes by the force of gravity into the bottle.

The top of the siphon is arranged at least

three meters from the ground, so that the pipe 20 may be approximately two meters. This pipe is of such diameter that it may retain in this length, about one liter of water, after the bottle has been filled with water. 70

When the water to be bottled contains a certain quantity of free carbonic acid, as in the case of Forges water, a portion of the gas dissolved in the water expands in the bottle, owing to the vacuum therein. The column of water in the pipe 20, which is in practice about two meters high, as aforesaid, rests on the gases which have a tendency to escape. This easily compresses the gases and in passing therethrough dissolves them, 80 so that the water retains its entire gaseous content. As soon as the filling operation has been completed, the cock 16 is closed and the pipe 20 remains full of water until the cock is again opened for the subsequent filling of a bottle. The reestablishment of the flow of the water in the siphon after each bottle is filled prevents the water from becoming contaminated.

In order to more fully insure the exclusion of the air during the movement of the bottle from the filling point to the corking point, the mouth of the bottle may be moved in an atmosphere of carbonic acid contained in a suitable hood, not shown. 95

Fig. 2 discloses a modified apparatus for carrying out the method where medicinal waters, comprising useful solid matters and carbonic acid, are bottled. Referring particularly to this figure, the water circulates in a siphon 24-27 which is arranged between the source 25' and the basin 26 on the lower level. A tank 22 is in open communication with a vacuum pump, not shown, which works continuously. This tank is connected, by means of a pipe 31 having a cock 32 therein, to a disk 33, on which is placed and packed an auxiliary dome 34. The pipe 31 passes through the disk 33 and rises to a sufficient height within the dome, 110 so that it will not be submerged, when, owing to carelessness of the operator, the water rises in the dome. A pipe 35 extends through the center of the disk 33 and terminates at the casing 9. This pipe is provided with a cock 8 which is located between the casing 9 and the dome 34. A pipe 37 extends downwardly from the dome 34, but does not pass beyond the upper face of the disk 33 and is provided with a suitable stop cock. The water inlet 20 is branched directly from the siphon 24-27 and terminates in the casing 9, communicating with the pipe 35 at this point. The water inlet pipe 20 is provided with a stop cock 16. 120

When the water is bottled by the apparatus disclosed in Fig. 2, the operation is as follows:—

Previous tests of the water which is to be bottled having shown the quantity of 130

dissolved carbonic acid therein, a dome 34, which is calculated in accordance with the test in a manner which will later appear, is placed on the disk 33. The bottle 18 is located on the disk 25 of the machine having been previously filled with carbonic acid at atmospheric pressure. The volume of the selected dome 34 is such that after the carbonic acid, which fills the bottle 18 at the 10 atmospheric pressure, has passed into the dome from the bottle, its pressure is reduced to such a point that the water which, in the meantime has been introduced into the bottle, contains only the carbonic acid which it 15 contained before its introduction into the bottle. The dome having been put in place, the cock 32 is opened, the cocks 8 and 37 remaining closed. By this operation, a 20 vacuum is produced in the dome 34, and then the cock 32 is closed. The bottle 18 filled with greater portion of the carbonic acid at atmospheric pressure is placed on the disk 25, the neck being brought under the casing 9. The cock 8 is opened, the cock 25 16 remaining closed and the carbonic acid contained in the bottle passes into the dome 34. The cock 16 is then opened and the water fills the bottle 18 expelling what remains of the carbonic acid. The entire volume of the gas brought into the bottle by the entrance of the water is forced into the dome 34 and its pressure, when it occupies this dome, is equal to the pressure of the gas within the water. After the bottle is 35 filled, the cock 16 is closed.

If, owing to the late closing of the cock 16, the water gets into the dome 34 through the pipe 35, it will fall back on the disk 33 and the cock 37 may then be opened to 40 drain the dome. The disk 33 is so constructed that it may receive domes of various

sizes, so that they may be interchanged, as the requirement of the final pressure of the gas varies.

With the process described, the bottling 45 operation may be carried out, so that the water will contain all of the carbonic acid after the bottling operation that it contained before the same, and furthermore, all foreign matter will be excluded from the bottle. 50

I claim:

1. The method of bottling mineral waters and the like, containing a gaseous constituent, which consists in reducing the pressure in the container to a point not lower than 55 the tension at which the gaseous constituents of the water will escape, and then admitting the water to the container.

2. The method of bottling mineral waters and the like containing a gaseous constituent which consists in filling the container with a gaseous medium, then reducing the pressure of the gaseous medium in the container to a point not lower than the tension at 60 65 which the gaseous constituents in the water will escape, and then admitting the water to the container.

3. The method of bottling mineral waters and the like containing a gaseous constituent which consists in filling the container with carbonic acid gas, then reducing the pressure of the carbonic acid gas in the container to a point not lower than the tension at 70 75 which the gaseous constituents in the water will escape, and then admitting the water to the container.

In testimony whereof I affix my signature in presence of two witnesses.

PAUL LEONIDE BAUDRY.
